UNITED STATES PATENT OFFICE.

JOHN P. EUSTIS, OF NEWTON, MASSACHUSETTS, ASSIGNOR TO J. P. EUSTIS MFG. COMPANY, OF CAMBRIDGE, MASSACHUSETTS, A CORPORATION OF MAINE.

HOLDER FOR TOOTH-BRUSHES.

1,283,403.

Specification of Letters Patent. Patented Oct. 29, 1918.

Application filed June 29, 1917. Serial No. 177,728.

To all whom it may concern:

Be it known that I, JOHN P. EUSTIS, a citizen of the United States, residing at Newton, Massachusetts, have invented certain new and useful Improvements in Holders for Tooth-Brushes, of which the following is a clear, full, and exact description.

This invention relates to holders for tooth-brushes, more particularly to sterilizing holders; that is to say, a holder which contains a sterilizing agent into which the bristle portion of a tooth-brush may be dipped and a ventilating chamber in which the bristle portion of the brush may be held above the sterilizing agent, so that it may dry out. One of the objects of the present invention is to provide such a holder with means whereby the holder may be supported either directly on a wall or the wall support can be removed and the holder supported directly on a table or shelf. Another object of the invention is to provide a holder comprising three main parts; namely, a sterilizing chamber, a ventilating chamber and a supporting bracket, which may be rigidly combined for attachment to the wall of a bathroom, for instance. A further object of the invention is to provide improved means for grasping and holding the handle of a brush, such as a tooth-brush, so as to support the said brush. Other objects are to provide an economical, practical and efficient tooth-brush holder and sterilizer which is sanitary and the parts of which can be readily detached so that the holder can be cleansed.

These being among the objects of the present invention, the same consists of certain features of construction and combinations of parts to be hereinafter described and then pointed out in the claims, a desirable construction of which device is shown in the accompanying drawings, in which—

Figure 1 is a side elevation of the improved tooth-brush holder and sterilizer;

Fig. 2 is a vertical central section thereof;

Fig. 3 is a perspective view of the preferred form of supporting bracket;

Fig. 4 is an enlarged end view looking down upon the holder, the supporting bracket being omitted;

Fig. 5 is an enlarged transverse section on the line 5—5 of Fig. 2; showing a squeezer;

Fig. 6 is a detail view, in section on the line 6—6 Fig. 2, to show how certain parts abut; and

Fig. 7 is an enlarged detail section with the supporting bracket removed and showing the sterilizing container and ventilating chamber directly secured together.

In the drawings, the device is shown as provided with a bracket 10 which is provided with an upturned lug 11, suitably perforated so that said bracket, with the holder supported thereby, can be attached directly to a wall. Said bracket is provided with a horizontal collar 12 in the nature of a dished ring, resembling generally the frustum of a cone. Said collar will be referred to later more specifically, as it is especially designed for supporting the holder.

There is supported by and below the bracket 10, a container 13 for the sterilizing fluid, and said container is preferably composed of a glass bottle, and it is obvious that the said bottle may be long enough to contain the entire bristle portion of a tooth-brush when introduced therein; or said bottle or other container may be comparatively shallow so that the tip end only of a tooth-brush may be dipped into the sterilizing fluid. The neck 14 of the glass bottle or other container is provided with a screw thread 15, and the opening formed by the upper contracted edge of the collar 12 is of such size and is arranged on such a pitch or spiral curve that the exteriorly screw-threaded neck of the container 13 can be screwed into the collar 12.

The tooth-brush holder and sterilizer also comprehends a ventilating chamber 16 located above the container 13. Preferably said ventilating chamber comprises a metallic tubular shell 17 having ample lateral openings 18 formed by cutting out the metal and a top opening 18a. Said shell can be of any suitable ornamental design, and preferably to that end the outward cylindrical wall is made gridiform as shown, thereby constituting a skeleton, the openings 18 of which are of relatively large dimensions as

- compared with the bar-like skeleton portions between them. The said openings are so shaped and disposed that the bar-like portions of the gridiform or skeleton wall lying 5 between said openings are of substantially the same width as each other, said widths being of substantially the same dimensions from end to end of each of said portions. Located within the apertured shell 17 and 10 fitted tightly against the inner wall thereof, there is a perforated, cylindrical lining 19, which may be composed of reticulated material such as wire gauze of comparatively small mesh. Preferably this gauze is made 15 of nickel silver and the metal shell is preferably made of nickel silver, so that a fine finish may be obtained theron and particularly on the flat bar-like elements thereof, and the greatest possible salubrity secured. 20 Said gauze lining 19 is held in position in the metallic shell 17 by being expanded and lock seamed into the shell 17. Said gauze lining extends down to an inner annular bead 22 formed on the lower end of the 25 shell 17. In this way the metallic shell and its contained wire gauze lining 19 constitute one member of the device shown in Figs. 1 and 2, the container or closure base 13 a second member, and the bracket member a 30 third member.
- The lower end of the metallic shell 17 is provided with a screw-thread 23, and said end is of such size and the said thread of such pitch that said screw-threaded end can 35 be screwed onto the screw-threaded neck of the container 13. Inasmuch as the upper edge of the collar 12 of bracket 10 is formed on a screw-thread pitch, thus forming a segmental screw-thread, it will have a high 40 point at 24, and it will be seen that when the bracket 10 is screwed down upon the container 13 and the ventilating chamber 16 is screwed down as far as possible, the lower edge of the metal shell 17 will be brought 45 to a stop against the high point 24 of the bracket collar 12. In this way the three main members referred to will be firmly united. A segmental screw-thread as referred to is one in which the terminal points 50 or ends of the thread do not overlap.
- When the three members referred to are screwed together as in the construction shown, it is obvious that the three engaging screw-threads thereof are disposed so that 55 the interior one on the base 13 is sufficiently continued or extended beyond the exterior one of the three upon the ventilating chamber 16 to receive and support the screw-threaded bracket or member 10.
- 60 In use the device may be attached to a wall by means of the bracket 10. A tooth-brush 25 may now be sterilized in the sterilizing fluid contained in the container 13, which is done by introducing the bristle end of the brush through the open upper end of the

ventilating chamber 16 and pressing the tooth-brush down so as to dip the bristle portion thereof into the sterilizing fluid. The brush may now be elevated and sustained in elevated position in any suitable manner, so 70 that the bristle portion of the brush will be located in the ventilating chamber, as shown in full lines in Fig. 2.

If the lower part 13 is a mere base for the 75 device, it is obvious that the brush or other article may be dipped into or washed in the desired fluid and then be pushed through the gap between the closure lips which will hold it in position for airing.

Preferably the upper end of the ventilating chamber 16 is substantially closed, as by means of non-matching, slotted, rubber disks 26, 27, the outer edges of which are confined between the top ring 20 and the open upper end of the shell 17, said ring being secured by screws 21 to said shell. The slits in the rubber disks are such as to provide flexible lips 28 which are free from each other at the centers of the disks, and the lips of one disk overlap the lips of the other disk so 90 that they do not match. In this way a substantially complete closure is provided for the upper end of the ventilating chamber which, at the same time, provides a series of flexible gripping portions, adapted to permit 95 the bristle end of the brush to be pushed into the ventilating chamber, while said lips engage the handle of the brush and support the same where desired.

Preferably, also, there is provided at the 100 lower end of the ventilating chamber a radially slotted rubber disk 29 which is seated against a metal washer 29^a, in turn seated upon the bead 22. The slitting of the disk 29 provides inwardly extending, flexible lips 105 30 which form a squeezer adapted to squeeze out superfluous sterilizing fluid from the bristle portion of the brush as the brush is raised into the ventilating chamber. Said rubber disk 29 also provides a soft packing 110 between the container 13, for protecting the latter against leakage if it be of glass, and the lower end of the shell 17.

Fig. 7 shows the container 13 and the 115 ventilating chamber 16 screwed directly together without the intervention or use of the supporting bracket 10. In this condition the holder may be placed directly upon a table or shelf.

It is obvious that the invention is susceptible of modification, as parts may be omitted, added and substituted without departing from the spirit and scope thereof as expressed in the claims.

What I claim as new is:—

1. In a device of the character described, the combination of two chambers, one for liquid and the other a ventilating chamber, said chambers having screw-threads whereby they are threaded together, the interior 130

one of said threads being extended outwardly beyond the length of the exterior thread, and supporting means having a collar which is threaded on to the extension of 5 said interior thread.

2. In a device of the character described, the combination of two chambers, one for liquid and the other a ventilating chamber, said chambers having screw-threads where- 10 by they are threaded together, the interior one of said threads being extended outwardly beyond the length of the exterior thread, and supporting means having a dished collar with an inner edge formed with 15 a screw-thread pitch so as to provide a segmental screw-thread, to engage the extension of said interior thread.

3. In a device of the character described, the combination of two members having mutually engaged screw-threads, the interior one of said threads being extended outwardly beyond the length of the exterior thread, and supporting means for said members, comprising a collar, a portion of which 25 has a screw-thread pitch and is engaged with the extension of said interior thread.

4. In a device of the character described, the combination of a fluid container and a ventilating chamber, together with a squeezer 30 located intermediately of said chambers.

5. In a device of the character described, the combination of a chamber for a sterilizing agent and having an exteriorly screw-threaded upper neck, an upper ventilating 35 chamber having an internally screw-threaded lower end, the thread of said neck extending downwardly beyond the other said thread, and a bracket having a collar, said collar having a segmental screw-thread edge for 40 engaging the extension of said screw-thread of said neck, said collar being adapted to constitute an abutment for said end of said upper chamber when screwed onto said neck.

6. In a device of the character described, 45 the combination of a base portion, supporting means for removably securing an object, said base portion and supporting means having one of them a neck and the other an open end complementary to and for receiving said 50 neck, and whereby they are removably secured together, said neck fitting in said open end so as to have a portion of its length located between said base portion and said end, and a bracket comprising an upright plate 55 and a collar fitted on said portion of said neck, and removable therefrom when said base portion and supporting means are separated, said collar being secured firmly between said base portion and supporting 60 means, when the two are connected together.

7. In a device of the character described, 65 the combination of a ventilated chamber having a top opening, a closure base for the bottom of said chamber, flexible lips nor- mally closing said opening and an internal

ring secured to said chamber, said lips being held between said ring and chamber and constituting means for automatically grasping an article and holding it suspended in 70 said chamber for airing it.

8. In a device of the character described, the combination of a ventilated chamber having a top opening, a closure base for the bottom of said chamber, said chamber and closure base having mutually engaging 75 screw threads, the interior one of said threads extending outwardly beyond the length of the exterior thread, means normally closing said opening, for automatically grasping an article and holding it suspended in 80 said chamber for airing it, and supporting means for said chamber and base comprising a collar, a portion of which collar is threaded and engaged with the extension of said interior thread. 85

9. In a device of the class described, the combination of a body provided with an opening, and two adjacent closely arranged series of flexible lips normally closing said opening, the lips of each series being out of 90 match with those of the other series and constituting means for automatically grasping an article to hold it supported on said body.

10. In a device of the class described, the combination of a base portion, a ventilating 95 chamber having supporting means for sustaining an object within said chamber, screw means detachably connecting said ventilating chamber with said base portion, and a bracket comprising a screw collar which is 100 screwed onto said screw means and thereby adapted to form a support for said base portion and chamber.

11. In a device of the character described, the combination of a base member, a top 105 member, one of said members having a neck, supporting means having a collar in which said neck is received, and means for detachably connecting said members through the medium of said neck, and for forcing said 110 collar in contact with said members, said collar and said detachable means having the same approximate diameters at their connecting surfaces whereby said collar is firmly attached by the conjoint action of said base 115 member and top member which engage with it.

12. In a device of the character described, the combination of a base member provided with a neck, supporting means having a collar in which said neck snugly fits, and a top member having a detachable connection with 120 said neck, and the connecting surfaces of said collar, neck and top member having the same approximate diameter whereby said 125 collar is firmly attached by the conjoint action of said base member and top member which engage with it.

13. In a device of the character described, the combination of a base member provided 130

with a neck, supporting means having a collar in which said neck snugly fits, and a hollow sheet metal top member having a screw-threaded connection with said neck, whereby when said top member is screwed home against said collar, the said collar is firmly engaged by and between said two members.

Signed at Cambridge, Mass., this 27th day of June, 1917.

JOHN P. EUSTIS.
